US0D1088359S

(12) **United States Design Patent** (10) Patent No.: **US D1,088,359 S**
(45) Date of Patent: ** Aug. 12, 2025

(54) **HEADGEAR**

- (71) Applicant: **The ESAB Group Inc.**, North Bethesda, MD (US)
- (72) Inventors: **Kevin Beckerdite**, Azle, TX (US); **Muhammad Khan**, Prosper, TX (US); **Azfar Kamal**, Frisco, TX (US); **Matthew Tanner**, Whitesboro, TX (US)
- (73) Assignee: **THE ESAB GROUP, INC.**, North Bethesda, MD (US)

(**) Term: **15 Years**

(21) Appl. No.: **29/848,251**

(22) Filed: **Aug. 1, 2022**

(51) LOC (15) Cl. **02-99**

(52) U.S. Cl.

USPC **D29/122**

(58) **Field of Classification Search**

USPC D29/108, 109, 110, 122
CPC A41D 13/1107; A41D 13/1161; A41D 13/1184; A62B 1/00; A62B 1/06; A62B 1/08; A62B 1/10; A62B 1/12; A62B 1/14; A62B 1/16; A62B 1/18; A62B 1/20; A62B 17/00; A62C 2/00; A62C 3/00; A62C 3/07; A62C 8/00; A62C 11/00; A62C 11/005; A62C 13/00; A62C 13/003; A62C 13/006; A62C 13/02; A62C 13/22; A62C 13/62; A62C 13/64; A62C 13/66; A62C 13/68; A62C 13/70; A62C 13/72; A62C 13/74; A62C 13/76; A62C 13/78; A62C 35/20; A62C 99/00; A62C 99/0009; A62C 99/0018; A62C 99/0027; A62C 99/0036; A62C 99/0045; A62C 99/0054; A62C 99/0063; A62C 99/0072; A62C 99/0081; A62C 99/009

(57) **CLAIM**

The ornamental design for headgear, as shown and described.

DESCRIPTION

FIG. 1 is a front perspective view of a headgear; FIG. 2 is a rear perspective view of the headgear of FIG. 1; FIG. 3 is a front view of the headgear of FIG. 1; FIG. 4 is a rear view of the headgear of FIG. 1; FIG. 5 is a left side view of the headgear of FIG. 1; FIG. 6 is a right side view of the headgear of FIG. 1; FIG. 7 is a top view of the headgear of FIG. 1; and, FIG. 8 is a bottom view of the headgear of FIG. 1. The broken lines illustrate portions of the headgear that form no part of the claimed design.

1 Claim, 8 Drawing Sheets
